(57) **CLAIM**

The ornamental design for a tiered stand, as shown and described.

DESCRIPTION

FIG. 1 is a top plan view of a tiered stand showing our new design;

FIG. 2 is a bottom plan view thereof;

FIG. 3 is a front elevation view thereof;

FIG. 4 is a rear elevation view thereof;

FIG. 5 is a right side elevation view thereof; and,

FIG. 6 is a left side elevation view thereof.

The broken lines illustrating the stand packaging in FIGS. 1–6 are environment, while the remaining broken lines in FIGS. 1–6 illustrate portions of the tiered stand that form no part of the claimed design.

1 Claim, 6 Drawing Sheets
